SNOWSHOE SANDAL

George M. Rintamaki, Newberry, and Leslie H. Powis, Lansing, Mich.

Application August 30, 1941, Serial No. 409,080

2 Claims. (Cl. 36—4.5)

Our invention relates to improvements in snowshoe sandals or harnesses whereby the foot of the wearer is flexibly but securely attached to the snowshoe, and the primary object of our invention is to provide a simple and more efficient arrangement of this type, which is characterized by less lost motion between the foot and the snowshoe and which reduces the wear upon the parts involved.

Other important objects and advantages of our invention will be apparent from a reading of the following description taken in connection with the appended drawing, wherein for purposes of illustration we have shown a preferred embodiment of our invention.

In the drawing—

Figure 1 is a fragmentary top plan view showing a snowshoe equipped in accordance with the present invention.

Figure 2 is an enlarged transverse vertical sectional view taken through Figure 1 along the line 2—2.

Figure 3 is an enlarged top plan view of the sandal or harness partly broken away to show the reinforced and non-stretchable rubber portions and the live stretchable rubber portions.

Figure 4 is a top plan view of the sole plate partly broken away to show the fabric reinforcement thereof.

Referring in detail to the drawing, the numeral 5 generally designates a substantially conventional form of snowshoe involving the usual cross piece 6, the toe-string 7, and the thongs 8 which tie the sandal or harness in place on the snowshoe.

In accordance with the present invention the sandal or harness is composed of a sole plate 9 which is transversely elongated with respect to the snowshoe and has a substantially straight rear edge 10, a slightly rearwardly curved front edge 11 and triangular ends 12 and 13. The sole piece is made of rubber and fabric for strength, wearing qualities, and durability and to avoid undesired stretch therein.

The top piece of the sandal which is generally designated 14 has a fore-part 15 matching in shape and extent the sole plate 9, and the portion 15 and the sole plate 9 are superposed in exact registry and vulcanized together at their ends. The portion 15 of the member 14 being longer than the sole plate, the result is an upward bowing of the intermediate portion of the part 15 as illustrated in Figure 2 of the drawing to provide a toe receptacle.

Eyelet rivets 16 are placed through the vulcanized ends of the assembly on a forward and inward bias as indicated, these rivets being located sufficiently forwardly to avoid lifting of the

tail of the snowshoe and to correct unnatural toe-down motion present because of the construction of many other snowshoe sandals.

From the points indicated by the numerals 17 5 the fabric reinforcement 18 of the top piece 14 stops and the horseshoe-shaped heel piece 19 whose legs project from the points 17 is formed of pure stretchable rubber which conforms to the shape and motion of the wearer's foot and

10 ankle.

The usual thongs 8 are placed through the eyelets 16 in the usual manner to connect the sandal or harness to the snowshoe. It will be observed that the heel piece 19 acts as automatically adjusting heel straps which do not slip up and down to cause lost motion and wear on the snowshoe.

Although we have shown and described herein a preferred embodiment of our invention, it is to be definitely understood that we do not wish to limit the application of the invention thereto except as may be required by the scope of the subjoined claims.

Having described the invention, what is claimed as new is:

25 1. A snowshoe harness comprising a sole plate to rest on the snowshoe, an upwardly bowed top plate overlying said sole plate with its ends registered with the ends of the sole plate, means securing said ends together, thong accommodating eyelets traversing said registered ends of the sole plate and top plate and arranged to pass thongs for attaching the harness on the snowshoe, said sole plate and said top plate being formed of relatively non-stretchable material, and a non-adjustable U-shaped heel strap having its legs secured to extend rearwardly from transversely spaced points along the rear edge of said top plate, said heel strap being of flexible and stretchable material.

30 2. A snowshoe harness comprising a sole plate to rest on the snowshoe, a top plate substantially coextensive with and overlying said sole plate, means securing together the registered ends of the sole plate and said top plate, thong accommodating eyelets in said registered ends and arranged to accommodate the usual thongs for attaching the harness on the snowshoe, said eyelets being located at the forward part of the 35 harness, and a U-shaped heel strap having its legs secured to extend rearwardly from transversely spaced points along the rear edge of said top plate, said sole plate and said top plate relatively non-stretchable and formed of fabric reinforced rubber, and said heel strap being formed of stretchable live rubber.

GEORGE M. RINTAMAKI.
